UNITED STATES PATENT OFFICE

172,423

RELIGIOUS MEDAL OR SIMILAR ARTICLE

Leo H. Herman, St. Louis, Mo.

Application May 29, 1953, Serial No. 25,246

Term of patent 14 years

(Cl. D29—2)

To all whom it may concern:

Be it known that I, Leo H. Herman, a citizen of the United States, residing in St. Louis, State of Missouri, have invented a new, original, and ornamental Design for Religious Medal or Similar Article, of which the following is a specification, reference being had to the accompanying drawing, forming a part thereof.

Fig. 1 is a plan view of the religious medal or similar article; and

Fig. 2 is a view taken from the bottom of Fig. 1.
I claim:

The ornamental design for a religious medal or similiar article, as shown.
